UNITED STATES PATENT OFFICE

138,669

DESIGN FOR A LAWN MOWER

George W. Davis, Richmond, Ind., assignor to
G. W. Davis Corporation, Richmond, Ind.

Application June 25, 1943, Serial No. 110,530

Term of patent 7 years

(Cl. D40—1)

To all whom it may concern:

Be it known that I, George W. Davis, a citizen of the United States, residing at Richmond, in the county of Wayne and State of Indiana, have invented a new, original, and ornamental Design for Lawn Mowers, of which the following is a specification, reference being had to the accompanying drawing, forming a part thereof.

In the drawings, Fig. 1 is a perspective front view of a lawn mower, showing my new design.

Fig. 2 is a perspective rear view of such design.

Fig. 3 is a side elevational view of one of the wheels shown in Figs. 1 and 2, and

Fig. 4 is a side elevational view of a frame member shown in the same figures.

The dominant features of the lawn mower of my design are shown in full lines in the drawings.

I claim:

The ornamental design for a lawn mower, as shown and described.

GEORGE W. DAVIS.
